UNITED STATES PATENT OFFICE

157,804

RAIN GAUGE

Frederick L. Vernon, Newton, Iowa

Application June 25, 1947, Serial No. 139,910

Term of patent 7 years

(Cl. D52—7)

To all whom it may concern:

Be it known that I, Frederick L. Vernon, a citizen of the United States, residing at Newton, in the county of Jasper and State of Iowa, have invented a new, original, and ornamental Design for a Rain Gauge, of which the following is a specification, reference being had to the accompanying drawing, constituting a part thereof.

Fig. 1 is a perspective view of a rain gauge, showing my new design;

Fig. 2 is a side elevation thereof; and

Fig. 3 is a plan view thereof.

I claim:

The ornamental design for a rain gauge, substantially as shown.

FREDERICK L. VERNON,
